UNITED STATES PATENT OFFICE.

AXEL F. HJORT, OF CHICAGO, ILLINOIS, ASSIGNOR TO BRUNSWICK-BALKE-COLLENDER CO., A CORPORATION OF DELAWARE.

BILLIARD-TABLE.

1,119,160.

Specification of Letters Patent.

Patented Dec. 1, 1914.

Application filed August 3, 1914. Serial No. 854,827.

To all whom it may concern:

Be it known that I, AXEL F. HJORT, a citizen of the United States, and a resident of the city of Chicago, in the county of Cook and State of Illinois, have invented certain new and useful Improvements in Billiard-Tables; and I do hereby declare that the following description of my said invention, taken in connection with the accompanying sheet of drawings, forms a full, clear, and exact specification, which will enable others skilled in the art to which it appertains to make and use the same.

This invention relates generally to improvements in billiard tables, and it consists, essentially, in the novel and peculiar combination of parts and details of construction, as hereinafter first fully set forth and described and then pointed out in the claims.

In the drawings already referred to, which serve to illustrate my said invention more fully, Figure 1 is a fragmental plan of a convertible carom-pocket billiard table, disclosing one corner thereof with cushions positioned as for a pocket table and the opposite lateral corner thereof with a carom table cushion arrangement. Fig. 2 is a rear elevation of a cushion and cushion strip 25 for either a pocket or carom table in which are embodied elements of my invention. By rear elevation is meant the rear face which is, when in position, against the inner face of the cushion rail. Fig. 3 is a transverse, 30 vertical section of the just above indicated members, taken in line 3-3 of Fig. 2. Fig. 4 is a plan view of a cushion rail embodying my invention. Fig. 5 is an elevation of the inner face of said cushion rail and is 35 taken in the direction of the arrow pointer 5 in Fig. 4. By inner face is meant that face of the cushion rail which is adjacent to the slate bed when in place on a billiard table. Fig. 6 is a perspective view of a detail hereinafter referred to. Fig. 7 is a bottom plan of a cushion rail and a cushion strip and cushion located adjacent thereto, 40 illustrating quick acting holding means therefor, in released position, which devices embody my invention. Fig. 8 is a similar view but disclosing the holding means in operative position, tightly holding the cushion and cushion strip to the cushion rail. Fig. 9 is a transverse, vertical section

in line 9-9 of Fig. 7, the section of the cushion strip and cushion, however, being eliminated. Fig. 10 is a transverse, vertical section in line 10-10 of Fig. 8, the dotted parts in said figure being intended to indicate the relative position of said figure with respect to a table bed and frame, which latter are shown in dotted lines. Fig. 11 is a transverse vertical section of a cushion rail provided with a slightly modified type of cushion strip and cushion holding means. Fig. 12 is a perspective view of one of the holding fingers employed in my invention.

Like parts are indicated by corresponding characters or symbols of reference in all the figures of the drawings.

The use and employment of billiard tables provided with an extra set of cushions whereby the former may be converted from a pocket billiards to a carom billiards table and vice versa is now so well known as to need no further dilation thereupon. Suffice it then to say that this invention concerns itself with quick acting means for facilitating the rapid removal of a set of one type of cushions and cushion strips and the equally rapid replacement of a set of the other type; it being understood that simplicity of construction and cheapness of manufacture are important essentials of my invention.

To now better understand my invention, I first refer to Fig. 1 which is a fragmental plan of a convertible table designated as a whole by the letter A, in which the lower left hand corner is shown with strips and cushions S as employed in a pocket billiard table, while the opposite lateral corner is equipped with strips and cushions S', converting the said table into a carom table. And it is now to be noted that in the interchange from the cushions S to those designated S' neither the pockets P nor the pocket irons P' are in any way disturbed. In the plan, Fig. 1 already referred to, T indicates the longitudinal and T' the lateral or end cushion rails.

In Fig. 3 I indicate a vertical cross section of the cushion and strip S', but I desire to call attention to the fact that all cushions and strips S and S' are alike in cross section and mechanical elements, the only difference being in the length and a slight change in the level in the ends thereof, so

that when the member S' is referred to herein, the member S is indicated as well. These same remarks apply to the cushion rails T and T' . In Fig. 3, 10 indicates the cushion proper and 10^a the backing or cushion strip therefor, to which said cushion is securely glued or cemented. It is to be understood that the cushion 10 is a rubber compound and it and the strip 10^a are enveloped by a tensely drawn strip of billiard cloth 11, the free edges of which are tacked to the rear face of cushion strip 10^a along the upper and lower edges thereof by suitable tacks 12. Gained in the rear face of said cushion strip about medially of the width thereof and extending its entire length is a flat bottomed groove 13, Fig. 2, and into this groove is fitted a light sheet metallic plate or bar 14, which same is fastened in place by screws 15 or other suitable media. At spaced intervals of the length of the cushion strip 10' are formed transverse depressions 16, which extend from the bottom edge of said strip to near the upper edge of groove 13 and are of greater depth, all clearly seen in Fig. 3; and it will be observed that all but the lower portions of these depressions are covered by the metallic strip or bar 14.

In Figs. 4 and 5 are illustrated the cushion rails T' which are fastened to the table A, or rather the slate bed 100 thereof, by means of tap bolts and nuts 101 and 102 in the usual manner as indicated in dotted lines in Fig. 10. The ends of these cushion rails T' are cut away, curved, and fitted as at 110 for the reception of the ends of the pocket irons and pockets P and P' and as they are of typical design no further description is necessary. Formed on the inner face of this cushion rail T' , of like spacing and positioning as the depressions 16 on cushion strip S' , are flat bottomed recesses or depressions 20, along the vertical marginal walls of which are provided depressions 21 and 21^a of lesser depth for the reception of sheet metallic angle plates 22, the lower and shorter legs 23 of which extend outwardly and contiguous to the lower edge of the cushion rail T' and are fixed thereto by screws 24 or similar means, the upper ends of said plates being attached to and rendered flush with the inner edge of the cushion rail by screws 25.

At the upper ends of the angle plates 22 are produced cut outs 26 of a facial width equal to the width of depressions 20 and of a depth to permit of the free reception therein of the neck 27 of a depending lever 28, between the upper edge of said depressions 20 and the edge of cut out 26. In the lower and shorter leg 23, and extending a slight distance into the vertical member 22 is punched a slot 29 of similar width to slot 26, the purpose of which is to permit the

exit of the lower end 28^a of lever 28, and to allow of a certain amount of movement thereof as indicated in Figs. 9 and 10.

Depending lever 28 already referred to comprises essentially a perpendicular member 30 having the outwardly extending horizontally disposed neck 27, which terminates in an upwardly projecting finger 31. In the face of the member 30 a short distance below the neck 27 there is a short outwardly pointing lateral protuberance 32 which acts as a pivotal point for the vibration of lever 28.

Arranged in the upper portion of recess or depression 20, Figs. 5, 9, 10, and 11, there is a circular bottomed hole 33 adapted for the reception of a helical spring 34, the free end of which is adapted to exert an outward pressure against the member 30 of the lever 28 at a point adjacent the neck 27, and to maintain the protuberance or pivotal point 32 in contact with the inner face of the angle 22. The result of this pressure has two effects; first, that of maintaining the finger 31 away as far as possible from the inner face of the cushion rail T' ; and, second, by reason of the pivotal point or protuberance 32, causing the lower end 28^a of the lever 28 to assume a position adjacent the lower, bottom edge of the depression 20 as shown in Fig. 9.

It is now to be noted that if a movement of the lower end 28^a of lever 28 toward the wall 22 be initiated, the finger 31 will be caused to approach the inner face of the cushion rail T' in an evident manner. To accomplish this movement of the lower end 28^a of lever 28 there is provided an eccentric lever 40, pivoted by a screw 41 in the lower leg 23 aforementioned, and arranged to swing in a horizontal plane, with its eccentric surface 42 in contact with the lower end of lever 28. It is evident that partial rotation of eccentric lever 40 in one or the other direction will impart corresponding movement to the lower end of lever 28. A marginal finger flange 43 is provided for said eccentric lever for ease of manipulation, and, in Fig. 11, is disclosed a modification of said lever, the operation of which is self evident.

The operation of my device may now be described as follows: Assuming the parts to be in the position indicated in Figs. 7 and 9, the cushion with its cushion strip 10^a possessed of the recesses 16 is placed with its rear face adjacent the inner face of the cushion rail T' and the fingers 31 caused to enter their respective recesses 16 by pressing down upon the cushion and cushion strip until the same is in contact with the billiard cloth 50 upon the slate bed 100 indicated in Fig. 10. Each of the levers 40 is now partially rotated until each of the fingers 31 tightly grip the cushion strip and main-

tain the same against the cushion rail by pressure of contact. When properly adjusted and in operative position as just described, it will be found that the finger flanges 43 are in a plane parallel to the outer, lower, longitudinal edge of the cushion rails in a position practically out of sight and out of the way of players on the table.

10 While herein I have disclosed the preferred mode of practising my invention, I desire it understood that I may make such changes and alterations therein as might suggest themselves to the skilled mechanic or permitted under the doctrine of equivalents.

Having thus fully described by invention I claim as new and desire to secure to myself by Letters Patent of the United

20 States:—

25 1. A fastening means including a cushion and cushion strip or the like, there being receiving devices in the rear face of said strip, a cushion rail having depending levers therein, coacting with said receiving devices, and means for actuating said levers.

30 2. A fastening means including a cushion and cushion strip or the like, there being receiving devices in the rear face of said strip, a cushion rail having depending levers freely movable and vibratable therein, coacting with said receiving devices, and means for actuating said levers.

35 3. A fastening means including a cushion and cushion strip or the like, there being receiving devices in the rear face of said strip, a cushion rail having depending levers freely movable therein and vibratable about a protuberance on said levers, coacting with 40 said receiving devices, and means for actuating said levers.

45 4. A fastening means including a cushion and cushion strip or the like, there being receiving devices in said strip, a cushion rail having depending levers therein, the upper portion of said levers projecting beyond the face of said rail and co-acting with said receiving devices, and the lower portion thereof extending below said cushion rail, and means on the lower face of said rail actuating said levers.

50 5. A fastening means including a cushion and cushion strip or the like, there being receiving devices in said strip, a cushion rail having freely movable and vibratable depending levers therein, the upper portion of said levers projecting beyond the face of said rail and co-acting with said receiving devices, and the lower portion thereof extending below said cushion rail, and means on the lower face of said rail actuating said levers.

55 6. A fastening means including a cushion and cushion strip or the like, there being receiving devices in said strip, a cushion rail

having depending levers freely movable therein and vibratable about a protuberance on said levers, the upper portion of said levers projecting beyond the face of said rail and co-acting with said receiving devices, and the lower portion thereof extending below said cushion rail, and means on the lower face of said rail actuating said levers.

7. A fastening means including a cushion and cushion strip or the like, there being flush receiving devices in the rear face of said strip, a cushion rail having interior depending levers possessed of gripping fingers projecting beyond said rail and adapted to engage said receiving devices, and means on said rail actuating said depending levers.

8. A fastening means including a cushion and cushion strip or the like, there being flush receiving devices in the rear face of said strip, a cushion rail having interior depending levers freely movable and vibratable therein, possessed of gripping fingers projecting beyond said rail and adapted to engage said receiving devices, and means on said rail actuating said depending levers.

9. A fastening means including a cushion and cushion strip or the like, there being flush receiving devices in the rear face of said strip, a cushion rail having interior depending levers freely movable therein and vibratable about a protuberance on said levers and possessed of gripping fingers projecting beyond said rail and adapted to engage said receiving devices, and means on said rail actuating said depending levers.

10. A fastening means including a cushion and cushion strip or the like, there being receiving devices in the rear face of said strip, a cushion rail having depending levers therein co-acting with said receiving devices, and eccentric levers operating in a horizontal plane adapted to actuate said levers.

11. A fastening means including a cushion and cushion strip or the like, there being receiving devices in the rear face of said strip, a cushion rail having depending levers freely movable and vibratable therein co-acting with said receiving devices, and eccentric levers operating in a horizontal plane adapted to actuate said levers.

12. A fastening means including a cushion and cushion strip or the like, there being receiving devices in the rear face of said strip, a cushion rail having depending levers freely movable therein and vibratable about a protuberance on said levers, co-acting with said receiving devices, and eccentric levers operating in a horizontal plane adapted to actuate said levers.

13. A fastening means including a cushion and cushion strip or the like, there being receiving devices in said strip, a cushion rail

having depending levers therein, the upper portion of said levers projecting beyond said rail and co-acting with said receiving devices, and the lower portion thereof extending below said cushion rail, and eccentric levers on the lower face of said rail, operating in a horizontal plane to actuate said levers.

14. A fastening means including a cushion and cushion strip or the like, there being receiving devices in said strip, a cushion rail having freely movable and vibratable depending levers therein, the upper portion of said levers projecting beyond said rail and co-acting with said receiving devices, and the lower portion thereof extending below said cushion rail, and eccentric levers on the lower face of said rail, operating in a horizontal plane to actuate said levers.

15. A fastening means including a cushion and cushion strip or the like, there being receiving devices in said strip, a cushion rail having depending levers freely movable therein and vibratable about a protuberance on said levers, the upper portion of said levers projecting beyond said rail and co-acting with said receiving devices, and the lower portion thereof extending below said cushion rail, and eccentric levers on the lower face of said rail, operating in a horizontal plane to actuate said levers.

In testimony whereof I have hereunto set my hand in the presence of two subscribing witnesses.

AXEL F. HJORT.
